SCREW OPERATED VISE CLOSED BY
TREADLE OPERATED CAMJohn Weber, Beverly Hills, Calif., by decree of
distribution assignor to Virginia Weber

Application November 19, 1943, Serial No. 510,949

5 Claims. (Cl. 81—26)

1

This invention relates to bench vises, and more particularly to a vise adapted for use in production work wherein means are provided for actuating the movable jaw so as to leave the hands free to carry out operations upon the work held in the vise.

This application is directed to an improvement over the construction of the bench vise disclosed in the copending application of Harold R. Mahoney, Serial No. 486,966, filed May 14, 1943, now abandoned.

It is an object of this invention to provide a bench vise including a fixed jaw, a movable jaw, means for adjusting the relative position of the fixed jaw with relation to the movable jaw, and means operatively associated with said adjusting means whereby the movable jaw may be moved to clamping position with respect to the fixed jaw independently of the said adjusting means.

Another object of this invention is to provide an improved form of bench vise including a fixed jaw and movable jaw, a nut and screw, means for adjusting the movable jaw relative to the fixed jaw, and means operatively positioned within a cut-out formed in the said nut and adapted to be actuated from a foot treadle for moving the movable jaw into clamping position with reference to the fixed jaw.

Another object of this invention is to provide an improved form of bench vise applicable for use in rapid production work and which is particularly useful in carrying out short repetitive operations and which includes means for setting a movable jaw of the vise with relation to the fixed jaw thereof and a means for actuating the movable jaw to and from clamping position, and which means is operable from a foot treadle freeing the hands for use in the positioning and operation upon the work.

Other objects and advantages of this invention it is believed will be apparent from the following detailed description of a preferred embodiment thereof as illustrated in the accompanying drawings.

In the drawings:

Figure 1 is a side elevation partly in vertical section of the bench vise embodying my invention.

Figure 2 is a sectional end view taken substantially on the line 2—2 of Figure 1.

Figure 3 is a fragmental view taken substantially on the line 3—3 of Figure 1.

In the preferred embodiment of my invention as the same is illustrated in the accompanying

2

drawings there is illustrated a vise which includes a fixed jaw 1 carried in any suitable manner upon a base 2 upon which there is mounted upon a suitable guideway a movable jaw 3.

- 5 A customary adjusting screw 4 is journaled in the movable jaw 3 and is threaded within a nut 5 which is mounted on the base 2 within a guideway 6 in position to engage a stop shoulder 7 to limit the movement of the nut 5 toward the movable jaw 3. The nut is in turn positioned within a cut-out recess 8 formed within the fixed jaw 1. The nut 5 is extended through the open bottom of the sleeve which is secured to the movable jaw 3 and houses the screw 4.
- 10 15 Extending through and journaled within the fixed jaw is a cam shaft 9 upon which there is mounted a cam 10. The cam 10 is mounted within a cam recess 11 formed in the structure of the nut 5 so as to leave end shoulders 12 and 13 toward the forward and rearward ends of the nut 5. Secured to the cam shaft 9 is a lever 14. The lever 14 is provided with a plurality of holes 15, any one of which is adapted to receive the bent end of the clamp rod 16, thus providing optional variations of pressures below the jaws. The clamp rod 16 extends downwardly from the vise and extends through a hole formed in a foot treadle 17. Below the foot treadle 17 there is positioned upon the rod 16 a compression spring 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850

dog 28. The dog 28 is pivoted upon a pivot pin 29 carried by the treadle 17. The dog 28 is spaced outwardly from the edge of the treadle 17 or in the back part of same and provides a guide section 30 which acts with the edge of the treadle 17 to guide the movement of the treadle 17 along the clamp rod 26. The engaging portion 31 of the dog 28 is offset so that it will engage the ratchet teeth 27.

The screw 4 is customarily provided with an adjustment bar which I remove, leaving only the ball 32 upon the end of the screw. By the use of this ball the screw 4 may be rotated to adjust the position of the movable jaw 3 with relation to the fixed jaw 1 whereafter operations of the movable jaw are controlled by the foot treadle 17. The pressing of the foot treadle 17 causes the cam or eccentric 10 to engage the rear shoulder 11 of the cut-out formed in the nut 5 to move the movable jaw 3 backward to clamp the work. As the foot treadle is depressed, the dog 28 engages the teeth 27 of the ratchet bar 26, thereby holding the jaw 3 in clamping position against the work. In order to adjust the position of the eccentric or cam 10 with reference to the cut-out, there is provided upon the rod 16 the lock and adjustment nuts 19 and 20 which determine the normal or starting position of the cam 10 with relation to the shoulder 11. Thus by threading the said nuts along the rod 16 the compression exerted by the spring 18 against the treadle 17 is determined, fixing the position of return of the cam 10 when the treadle is released. When the treadle is released the cam or eccentric 10 engages the upper or forward shoulder 12, thereby moving the movable jaw away from the work permitting the work to be moved from between the jaws.

Having fully described my invention, it is to be understood that I do not wish to be limited to the details herein set forth, but my invention is of the full scope of the appended claims.

I claim:

1. In a mechanic's bench vise, the combination of a relatively fixed jaw, a relatively movable jaw, means on the fixed jaw for guiding the movable jaw toward or from the fixed jaw, a rotatable feed screw swiveled in the movable jaw, a non-rotatable nut member on the feed screw slidably mounted with respect to the fixed jaw, means for guiding the nut member, the nut member having a cut-out recess formed therein, a cam member mounted within the cut-out recess, a cam shaft carried by the fixed jaw and adapted to rotate the cam, a lever secured to the cam shaft, a treadle, and a rod connecting the lever and the treadle.

2. In a mechanic's bench vise, the combination of a relatively fixed jaw, a relatively movable jaw, means on the fixed jaw for guiding the movable jaw, a rotatable feed screw swiveled in the movable jaw, a non-rotatable nut member threaded on the feed screw and slidably mounted on the fixed jaw, means for guiding the slideable nut member, a stop on the fixed jaw for limiting the nut's movement toward the movable jaw, the nut having a cut-out recess, a cam member mounted in the cut-out recess, means for supporting the cam member within the recess, and means operatively connected to said supporting means for rotating the cam member about a fixed axis to

move the nut member whereby work may be clamped by the fixed and movable jaw or released therefrom dependent upon the direction of rotation of the cam member.

5. 3. In a mechanic's vise, the combination of a relatively fixed jaw, a relatively movable jaw, a screw swiveled within the movable jaw, a non-rotatable nut member threaded upon the screw, means on the fixed jaw for slidably guiding the nut member, and nut member having a cut-out recess formed therein, a cam shaft journaled within the fixed jaw, a cam carried by the cam shaft within the cut-out recess of the nut member in position to engage shoulders formed at the back end and top of the cut-out recess, an actuating lever secured to the cam shaft, a treadle, a rod operatively connecting the treadle and the lever, and spring means operatively connected with the rod adapted to urge the rod in a direction to rotate the cam in a direction to move the movable jaw away from the fixed jaw.
10. 4. In a mechanic's vise, the combination of a relatively fixed jaw, a relatively movable jaw, a rotatable screw swiveled within the movable jaw, a non-rotatable nut member threaded upon the screw, means on the fixed jaw for slidably guiding the nut member, the nut member having a cut-out recess formed therein, a cam shaft journaled within the fixed jaw, a cam carried by the cam shaft within the cut-out recess of the nut member in position to engage the back shoulder and top of the cut-out recess, an actuating lever secured to the cam shaft, a treadle, a rod operatively connecting the treadle and the lever,
15. 30. 35. spring means operatively connected with the rod adapted to urge the rod in a direction to rotate the cam in a direction to move the movable jaw away from the fixed jaw, and a pawl and ratchet means operatively associated with the foot treadle for holding the foot treadle in depressed position.

40. 5. In a mechanic's bench vise, the combination of a relatively fixed jaw, a relatively movable jaw, means on the fixed jaw for guiding the movable jaw toward or from the fixed jaw, a rotatable feed screw swiveled in the movable jaw, a non-rotatable nut member threaded on the feed screw, means on the fixed jaw for slidably guiding the nut member for motion relative thereto co-axially of the screw, a recess in the nut member, a cam 50 in the recess, a shaft rotatably mounted in the fixed jaw and secured to the cam, and means for turning the shaft.

JOHN WEBER.
